TWO-PARTY LINE TELEPHONE SYSTEM

Gerald Deakin, New York, N. Y., assignor, by
mesne assignments, to Western Electric Com-
pany, Incorporated, New York, N. Y., a corpo-
ration of New York

Application April 27, 1933, Serial No. 668,179

6 Claims. (Cl. 179—8.5)

This invention relates to two party line auto-
matic telephone systems.

One object of the invention is to provide a two
party line system wherein one party cannot be
5 interfered with during dialling or conversation
by any operation which may be performed by the
other party on the same line. Each station is
provided with an asymmetric device, such as a
rectifier of the dry type, and the rectifiers are con-
10 nected in such a manner that when one party's
telephone is in use, no current can flow through
the dial switch contacts or transmitter of the
telephone of the other party.

A further object of the invention is to provide a
15 system of the above mentioned type wherein the
service is secret, so that one party cannot listen
in to the conversation while the other party is
talking to a called line.

A further object of the invention relates to the
20 provision of means whereby either one of the
two parties can call and talk with the other by
way of the central office.

Referring to the drawing, Figure 1 shows the
25 circuits of the two party line stations and certain
connections at the central office. Figure 2 shows a
modified circuit for a subscriber's station to be
used when secrecy is desired and Figure 3 shows a
subscriber's circuit which may be employed for
30 revertive calling.

In Figure 1, the circuits shown for stations A
and B are identical except for their connection to
the lines *a*, *b* connecting the stations to the cen-
35 tral office C. In station A, current passes from
line *b* through rectifier 1, dial contacts 2, trans-
mitter 3, switch hook contact 4, winding 5 of in-
duction coil 6 back to line *a*. The receiver 7 is
40 associated with this circuit by the winding 8 of in-
duction coil 6 and condenser 9 and also by switch
hook contact 10. The ringer 11 is connected to
the circuit as shown and to earth.

In the circuit for station B, current must be
45 received over line *a*, as the rectifier 1 is connected
in such a way as to prevent the passage of current
therethrough when the current arrives over line
b. Winding 5 of the induction coil 6 is connected
50 to line *b* instead of line *a* as was the case with
station A.

At the central office C, the lines *a* and *b* ter-
minate at terminal 12 for party A at contacts 13
55 and 14 respectively and at terminal 15 for party
B at contacts 16 and 17 respectively. Line relay
40 serves for party A, its winding connected to
negative battery being also connected through
windings of cut-off relay 19 is connected to negative

battery and to the contacts 20 and 21 of the ter-
minals 12 and 15 respectively.

Line relay 22 serves for party B, its winding
being connected to negative battery on the one
hand, and through contact 23 of cut-off relay 19
5 to line *b* on the other hand.

Test contact 24 of terminal 12 is adapted to be
connected to negative battery 25 through resist-
ances 26, contact 27 of line relay 22 when the
latter is deenergized, and contact 28 when line 10
relay 17 is energized. Test contact 29 of ter-
minal 15 is adapted to be connected to negative
battery 25 through resistance 26 at contact 39
when relay 22 is energized.

Service meters 31 and 32, whose windings are 15
connected to negative battery and to contacts 33
and 34 of terminals 12 and 15 respectively, are also
provided.

When party A lifts the receiver to make a call,
a circuit is completed from ground, ringer 11, 20
winding 8, receiver 7, contacts 10 and 4, winding
5, line *a*, contact 18, winding of line relay 17 to
negative battery. Line relay 17 operates and
places a test potential on contact 24.

Line relay 22 cannot operate because its cir-
cuit is blocked at the rectifier 1 of station A.

The lifting of the receiver also causes a line
finder (not shown) to operate in the well known
manner, and this finder selects the terminal 12
30 by reason of the test potential having been ap-
plied to contact 24. A connecting circuit (not
shown) now selects this line finder and con-
nects a current supply bridge (not shown) to
the line, negative potential being connected to
line *a*, and positive potential to line *b*. Cut-off
35 relay 19 now operates in the well known manner
breaking the circuits of line relays 17 and 22
(this relay has not operated) at contacts 18 and
23 respectively. Current now flows from the
40 current bridge through the circuit of station A,
but cannot flow through the circuit of station
B in the event the receiver at station B is lifted,
because it is blocked at rectifier 1 at that station.

The operation for station B is similar to the
above, except that in this case the current bridge
45 is oppositely connected, so that positive poten-
tial is now on the *a* line and current can pass
through rectifier 1 at station B, which current
however cannot pass rectifier 1 at station A.

As will be apparent from the description al-
ready given, the service meter belonging to the
calling station is adapted to be operated in the
well known manner to the exclusion of the serv-
ice meter of the other station which has not in-
50 initiated the call.

There being no completed circuit through the apparatus at station B when station A is calling, it is clear that the party at station B cannot interfere, although he may remove his receiver and operate his dial.

In the case of a call incoming from another line, positive potential will be placed on the *b* line if the call is for station A, whereas if the call is for station B, positive potential will be placed on the *a* line. Ringing current for station A is applied to the *b* line and for station B to the *a* line.

In the arrangement just described, when station A is involved in a call, it will be possible for the party at station B to remove his receiver and listen in to the conversation. In Figure 2 a circuit for the subscriber's station is shown which will make it impossible for the other party to even listen in. The same reference characters are used in this figure as were used in Figure 1, so far as the apparatus common to both are concerned. Instead of the direct connection between rectifier 1 and line *b* as was the case of station A, Figure 1, the current now passes through the winding of relay 35.

Condenser 36 is provided to permit the talking path from line *b* to reach the transmitter 3 without passing through the winding of relay 35 and rectifier 1. Contact 37, normally closed, forms a short circuit around receiver 7, so that the latter cannot become operative until relay 35 has been energized and contact 37 opened.

If it is desired to provide for revertive calling, the arrangement of Figure 3 may be used. Here a member 38 is provided so that in the case where relay 35 has been energized, and contact 37 opened, this member 38 will, upon the receiver 7 being lifted, mechanically hold contact 37 open. If relay 35 is not energized, the removal of the receiver 7 will not affect the armature of relay 35 in any way and such armature will be free to move thereafter in case relay 35 becomes energized, whereupon member 38 then mechanically holds it. The operation of relay 35 in this case will also place a short circuit around the rectifier 1 at contact 38.

Assuming that station *a* is calling station B, it will be clear that the initial operation at station A is similar to that as in Figure 1 or 2, and as member 38 holds contact 37 open, the current

can then be reversed at the central office as is the usual procedure in making such revertive calls, and the normal operation will take place at station B.

What is claimed is:

1. A two party automatic telephone exchange system comprising a rectifier at each station, a line circuit, a service meter individual to each station and located at the central office, and means including a finder switch for each station whereby only the service meter individual to one of said stations is adapted to be associated with the line circuit when said station originates a call.

2. A two party line forming a part of an automatic telephone exchange system, two subscribers' stations associated with said line, means including a rectifier at each station for rendering it inoperative when the other station is involved in a call with another party in the system, and means for disabling said rectifier means to permit one of said two subscribers' stations to call and converse with the other of said two subscribers' stations.

3. In a subscriber's circuit arrangement for a two party line, a receiver, a rectifier in series with a relay, a short circuit normally maintained about said receiver but adapted to be broken upon the passage of current through said rectifier and relay.

4. In a subscriber's circuit arrangement for a two party line a switch hook, a receiver, a rectifier, a relay having an armature adapted to break a short circuit about said receiver upon the energization of said relay by current passing through said rectifier, and means associated with said switch hook for maintaining said armature in its operated position after current ceases to flow through said relay.

5. In a subscriber's circuit arrangement for a two party line means comprising a rectifier for isolating said circuit and means under the control of the subscriber for disabling said first mentioned means in the case of a revertive call when the line is otherwise free.

6. In a circuit arrangement for a subscriber's station for a two party line comprising in combination a receiver, a rectifier and a relay, said relay being adapted to control separate short circuits about said receiver and said rectifier.
